PHONOGRAPH

Charles Huenlich, Bloomfield, N. J., assignor to
 Thomas A. Edison, Incorporated, West Orange,
 N. J., a corporation of New Jersey

Application September 23, 1936, Serial No. 102,060

3 Claims. (Cl. 274—17)

This invention relates to phonographs, and more particularly to phonographs adapted at least at times for recordation, for example of dictation, upon a removable record.

In connection with such phonographs it is common practice to provide a warning or indicating means for apprising the dictator, or other person effecting or controlling the recordation, of an approach to the limit of recording space available on the record. Usually this means operates to supply a momentary or substantially instantaneous indication or warning at a predetermined interval, in respect of recording space or time, before the exhaustion of available recording space; accordingly after the operation of this means a dictator may continue his dictation for a brief period—for example for a number of words sufficient, in most instances, to complete a sentence or to close a letter—before replacing the record then in use with a fresh one. There has been available, however, no obvious measure of the recording space or time remaining after the operation of the warning or indicating means; the dictator has thus been left to choose between a conservatively prompt removal of the record, with possible waste of some available recording space, and an appreciable continuation of dictation, with the possibility of the terminal portion failing of recordation—frequently without his knowledge. Furthermore the dictator, concentrating his thoughts on the subject matter of his dictation and knowing that the indication he receives from the means in question is not fully final in its nature, may forget the indication during the permissible continuance of dictation and accordingly exceed that permissible continuance. If on the other hand the means in question be arranged to operate immediately prior to record space exhaustion, the dictator is confronted upon its operation with an inflexible requirement for an immediate cessation of dictation.

It is an object of the instant invention to so warn the dictator of the impending exhaustion of recording space as to provide for a permissible continuance of dictation of indicated duration.

It is another object more completely than heretofore to indicate the traversal of a predetermined terminal portion of the recording space.

It is another object to indicate differentially the beginning and substantial ending of traversal of such a predetermined terminal portion.

It is a further object to provide a generally improved system for warning of impending exhaustion of recording space.

Other and allied objects will more fully appear

from the following description and the appended claims.

In the description reference is had to the accompanying drawing, of which:

Figure 1 is a top plan view, with portions broken away, of a phonograph in which my invention has been incorporated;

Figure 2 is a fragmentary rear view of the phonograph showing, in normal position, parts which constitute a form of my improved warning means;

Figure 3 is another fragmentary rear view showing the same parts in another set of positions, which they occupy at substantially the beginning of traversal of the abovementioned terminal recording space portion; and

Figure 4 is still another fragmentary rear view showing the same parts in still another set of positions, which they occupy at substantially the ending of traversal of recording space.

There may first be described, with reference to Figure 1, the conventional portions of the phonograph of the drawing; these will be understood, however, to be illustrative only. Thus typically there is provided a mandrel 1 adapted to support a removable cylindrical record R. The shaft 2 of the mandrel is journalled in a bearing 3, which is secured to or formed from the stationary top-plate 4 of the phonograph. Shaft 2 and mandrel 1 are arranged for rotation by a pulley 5, through the medium of the clutch 6 which is engageable and disengageable at will to provide immediate control over the rotation; the pulley 5 is rotatably mounted on a short shaft 2' secured in standard 7, and is driven by a belt 8 from a motor (not shown) suspended below the top plate 4.

Above the mandrel 1 is arranged a recording and reproducing mechanism 13, conveniently referred to as a sound box. This may for example be provided with appropriate styli for engagement with the surface of a record R in well known manner, though no limitation to any particular form of this mechanism is intended. In Figure 1 the numeral 13' designates a recording stylus. In the operation of the phonograph the sound box is caused to travel longitudinally of the record, for example from left to right; thus when adjusted for recordation the particularly illustrated mechanism will engrave a continuous helical spiral groove in the record R, this groove being modulated (for example in depth) by sound or sound-representing energy appropriately supplied to the sound box. To effect the longitudinal travel of the sound box the latter is supported in a circular mounting 14' forming a portion of a carriage 14, 55

this carriage being slidably arranged on the longitudinal guide rods 15 and 16; during recordation or reproduction the carriage is driven slowly along these rods. This driving is accomplished by engagement of a feed nut 17 (secured to the carriage) with a feed screw 10 journaled in standards 7 and 7', the feed screw being rotated by shaft 2 through the medium of driving gear 12 on that shaft and driven gear 11 on the feed screw. To permit mandrel rotation without sound box travel during times of non-recordation or reproduction, there is provided a lever 18 movable in slot 19 in the carriage and arranged in accordance with its position selectively to engage and disengage the feed nut 17 with and from the feed screw 10 (by mechanism not here necessary to show). It will be understood that in the illustrated phonograph the exhaustion of recording space occurs when the recording stylus 13' in its rightward travel reaches substantially the right-hand extremity of the record R; the parts may of course be so arranged that thereafter further movement of the carriage 14 and sound box is prevented, by impingement of the carriage against standard 7.

In the phonograph so described I have incorporated my invention in a form arranged for the production of warnings or indications of audible nature, though no limitation to such nature is intended in the broader aspects of the invention.

According to the invention there are indicated or signalled both the beginning and the substantial ending of traversal of a predetermined terminal portion of the recording space. This may be done for example by the production of a momentary ring or other sound at such beginning, and of another ring or other sound at such substantial ending. Thus by the first sound the dictator is put on notice of the impending exhaustion of recording space. If the subject matter of his dictation permits he may now draw the dictation to an appropriate close; but if not he may continue freely, with positive assurance that recordation is still being effected, until he hears the second sound; thereupon he stops his dictation within a very few words, and changes records with the assurance that the available space on the first record has been efficiently utilized. The typical specific structure which I have illustrated for this action is now described, with special reference to Figures 2, 3 and 4:

Underneath the back carriage guide rod 16 and near the right-hand end of the phonograph is mounted a bell 25; this mounting is convenient to the standard 7' by means of a long-shank stud 26. The bell is held between the enlarged head portion 29 of the stud and a spacing sleeve 27 surrounding the stud between bell and standard, the stud passing through the standard 7' to be secured by the nut 26'. The enlarged stud head portion 29 is provided with the vertical slot 29'; and an arm 30 is centrally pivoted, to swing in this slot, by the horizontal cross-pin 31. The lower portion of the arm 30 is curved so that, when the upper portion is essentially vertical, the extremity of the lower portion is adjacent the bell 25; this extremity is formed into a clapper 30' for the bell. The normal position of the arm, illustrated in Figure 2, is one wherein the clapper is minutely spaced from the bell; this position is maintained by the tension spring 34, then fully closed, this spring being terminally fastened to the lower portion of the arm 30 and to a clip-washer 28 held between bell 25 and stud head portion 29.

The upper portion of the arm 30 is divided to

form left-hand and right-hand fingers 32 and 33, respectively (it being borne in mind that in the rear views of Figures 2, 3 and 4 these parts naturally appear in reverse arrangement). These fingers extend upwardly into the path of a trip member or pawl 35 which is pivotally mounted (at 36) to a lug 38 carried, underneath guide rod 16, by the carriage 14. The pawl 35 is provided with a finger-engaging face 35' of which the top, by impingement against lug 38, limits clockwise rotation of the pawl as seen in Figures 2, 3 and 4 to the position appearing in those figures; the normal position of the pawl, assumed by virtue of gravity, is substantially this position. The path of the bottom of the pawl face 35' is shown in Figure 2 as the line P.

As the carriage travels from left to right of the phonograph (i. e., in a leftwardly direction as appearing in Figure 2), the pawl face 35' is eventually brought into contact with the finger 32. As the travel continues the arm 30 is slowly rotated about its pivot pin 31 (in a clockwise direction as seen in Figure 2) so that the tip of finger 32 describes an arc shown in Figure 2 as terminating at the point A on line P; when this point is reached the parts will have assumed the positions illustrated in Figure 3, which may correspond for example to a stylus 13' position, longitudinally of the record, as indicated by the line W₁ in Fig. 1. Immediately thereafter the finger 32 will be released by the pawl, since further arcuate movement of the finger tip would be below the line P; upon this release the arm 30 will fly clockwise about its pivot in response to the spring 34, which has been expanded by the arm rotation, the inertia of the arm causing it to overshoot its normal position so that the clapper 30' strikes the bell 25. Thus is provided an audible indication of the beginning of traversal of a predetermined terminal portion of the recording space—i. e., the space on the record from the line W₁ rightwardly.

As the carriage continues its travel the pawl face 35' is presently brought into contact with the finger 33. As the travel further continues the arm 30 is again slowly rotated about its pivot pin 31 so that the tip of finger 33 described the arc shown in Figure 2 as terminating at the point B on line P; when this point is reached the parts will have assumed the positions illustrated in Figure 4, which may correspond for example to a stylus 13' position, longitudinally of the record, as indicated by the line W₂ in Figure 1. Immediately thereafter the finger 33 will be released by the pawl and, as in the case of release of the finger 32 above described, the clapper 30' will again strike the bell 25. Thus is provided an audible indication of the substantial ending of traversal of the predetermined terminal portion of the recording space—and of course of the recording space as a whole.

It will be obvious that the positions of the sound box and stylus at the times of the two sounds will be determined by the positions (A and B) which have been assumed by the tips of the fingers 32 and 33 just as they are disengaged by the pawl, these positions A and B being in turn determined by the position of the pivot pin 31 and the distances of the finger tips therefrom. I prefer so to arrange the last mentioned parameters that the second sound will occur just before the exhaustion of recording space, and the first sound therefore by an interval of the order of one-half minute (assuming uninterrupted travel of the carriage during that interval).

In accordance with my invention I may provide

a distinction between the two sounds or other indications; in the illustrated embodiment such a distinction is made in the amplitudes of the sounds. This amplitude is obviously determined by the angular length of the arc through which the arm 30 is moved between normal position and the position of release by the pawl; for any given distance of finger-tip from pivot 31 this arc length is determined by the angle formed between a line from finger-tip to pivot and a line from pivot to clapper. In the illustrated embodiment I have so chosen these angles for the respective finger-tips, in view of their distances from the pivot, that the arc terminating at point A is greater than that terminating at point B—in other words, so that the first of the sounds will be the louder, this relationship obviously, however, may be reversed if desired.

Alternatively or additionally to a differentiation in the sound or other signal itself, I may provide a differentiation by auxiliary visible means; typical such means have been illustrated in Figure 1. Herein will be seen, at the front of the phonograph, an index holder 42 wherein is intended for insertion with each record inserted upon the mandrel 1 a corresponding index scale 40; secured to the carriage 14 and overhanging the index holder and scale is an indicator 43, the position of the right-hand edge of which indicates a position longitudinally of the index scale corresponding to the position of the stylus 13 longitudinally of the record. Such index holder, scale and indicator are themselves in common use, the slip usually being adapted to be marked by the dictator to note corrections, lengths of letters, etc. According to the instant invention there may be printed on the index scale, in position to be traversed by the indicator 43 as the stylus traverses the predetermined terminal recording space portion, a sub-scale S, the beginning and ending of this sub-scale comprising for example prominent lines or markings il-

lustrated as 45 and 45', respectively. It will be understood that the right-hand edge of indicator 43 will be over the marking 45 when the first of the two above described sounds occur, and over the marking 45' when the second occurs. Thus upon hearing of one of the sounds by the dictator, a glance at the sub-scale S instantly resolves any question he may entertain as to which sound has been heard. Furthermore, this sub-scale, together with a conception rapidly gained through usage as to the approximate recording time which its length represents, enables the dictator much more accurately to estimate his ability to complete his dictation in any instance within the limits of the available recording space.

I claim:

1. A phonograph having, in combination, a support for and means for recording on a record, means for causing traversal of the record by the recording means, and mechanical means responsive to said recording means in its traversal for producing a plurality of predeterminedly separated and mutually distinctive audible warnings of the termination of said traversal.

2. A phonograph having, in combination, a support for and means for recording on a record, means for causing traversal of the record by the recording means, a bell, a striker for said bell, and a plurality of means associated with said striker for rendering the same responsive to said recording means at a respective plurality of points in the terminal portion of said traversal.

3. A phonograph having, in combination, a support for and means for recording on a record, means for causing traversal of the record by the recording means, a bell, a pivoted striker for said bell, a plurality of fingers extending from said striker, and a pawl connected with said recording means and adapted to engage said fingers at respectively different points in said traversal.

CHARLES HUENLICH.
